United States Patent

Des. 237,902
Patented Dec. 2, 1975

237,902

PAIR OF SPECTACLES

F. Forrest Eaton, Rochester, N.Y., and Richard R. Maiese, Sturbridge, Mass., assignors to American Optical Corporation, Southbridge, Mass.

Filed Apr. 25, 1972, Ser. No. 250,115

Term of patent 14 years

Int. Cl. D16—06

U.S. Cl. D57—1 F

FIG. 1

FIG. 2

FIG. 3

FIG. 1 is a front elevational view of a pair of spectacles embodying our new design;

FIG. 2 is a top plan view thereof, the temples being broken away for convenience of illustration; and

FIG. 3 is an elevational view of one side of the pair of spectacles, the opposite side thereof being of substantially the same appearance.

We claim:

The ornamental design for a pair of spectacles, as shown and described.
